UNITED STATES PATENT OFFICE

142,360

DESIGN FOR A TOY FARM IMPLEMENT

Herbert Hieb, Des Moines, Iowa

Application November 24, 1944, Serial No. 116,666

Term of patent 7 years

(Cl. D34—15)

To all whom it may concern:

Be it known that I, Herbert Hieb, a citizen of the United States, and a resident of Des Moines, in the county of Polk and State of Iowa, have invented a new, original, and ornamental Design for a Toy Farm Implement, of which the following is a specification, reference being had to the accompanying drawing, forming part thereof, in which:

Fig. 1 is a top view of a toy farm implement showing my new design;

Fig. 2 is a rear view of the same;
Fig. 3 is a front view of my new design;
Fig. 4 is a bottom view of the same;

Fig. 5 is a side elevation of my new design looking toward the right in Fig. 1; and

Fig. 6 is a sectional view taken on the line 6—6 in Fig. 2.

I claim:

The ornamental design for a toy farm implement, substantially as shown.

HERBERT HIEB.
